Kings Hudson & Kent
et al.

UNITED STATES PATENT OFFICE.

PAUL W. COPPOCK, OF SOUTH EUCLID, OHIO, ASSIGNOR TO MAURICE J. COPPOCK, OF PERRY, OHIO.

OIL STOVE.

Application filed September 21, 1925. Serial No. 57,547.

This invention relates to stoves and more particularly to oil stoves.

It is customary in oil stoves employing wicks to have the burners arranged in a straight line so that they are all easily accessible from the front of the stove for the purpose of lighting the burners and for cleaning. It is one of the objects of this invention to provide an improved arrangement of burners in which some are located behind those at the front of the stove, this arrangement affording a design that is shorter and more compact than the stoves now commonly used.

It is a further object of the invention to so arrange the burners that any of them may be conveniently moved to the front of the stove for the purpose of lighting and cleaning and also to permit the use of any particular burner with different openings in the stove top.

A further object of the invention is to provide a more compact burner arrangement, than has been heretofore used, in which the fuel reservoir is located between the burners so that all of them may be uniformly supplied with fuel.

A further object of the invention is to provide a construction in which the fuel reservoir is located between the burners and yet thoroughly insulated from the heat that is generated in the burners.

Other objects of the invention and the features of novelty will be apparent from the following description taken in connection with the accompanying drawings in which Fig. 1 is a plan view of a stove embodying my invention; certain parts being broken away and other parts being shown in section;

Fig. 2 is a section on the line 2-2 of Fig. 1;

Fig. 3 is an enlarged vertical section through the fuel reservoir; and,

Fig. 4 is a section on the line 4-4 of Fig. 1.

In the drawings I have illustrated the application of my invention to a stove having four burners which are arranged in the form of a square, the burners being indicated at 10, 11, 12 and 13. The details of construction of the burners are not shown in the drawings as they form no part of the present invention but it will be understood that any of the usual forms of wick or, so

called, wickless burners may be used. The burners are enclosed in a square casing 14 having the doors 15 at the front thereof which may be opened to permit access to the burners and to the fuel reservoir. The top of the stove is indicated at 16 and has the usual openings 17 over the different burners. The casing 14 is supported on legs 18 and rods 19 extend diagonally across the interior of the casing between the corners thereof, and support, at the center of the casing, a step-bearing 20.

A block 21 is supported on the step-bearing 20 and has a trunnion 22 cooperating therewith so that the block 21 may be rotated. Fuel supply pipes 23 extend radially from the block 21 and support the different burners.

A fuel basin or sump 24 is supported on the block 21 by means of a pipe 25, fuel being fed through the pipe 25 and the ports 26, in the block 21, to the different pipes 23. The sump 24 is arranged in a central chamber which is formed by the walls 27 and 28, these walls being spaced apart to provide a jacket space 29 through which air is permitted to circulate. The walls 27 and 28 are preferably of cylindrical form and the top of the chamber 30, which is enclosed thereby, as well as to the upper end of the jacket space 29, are closed by a cover 31 having an upwardly projecting flange 32 which is rotatably arranged in a central opening in the top 16. A perforated cap 33 is fitted in the flange 32 to close the opening therein. The cover 31 has a peripheral flange 34 which fits over the wall 28.

The walls 27 and 28 are supported on the pipes 23 and held in properly spaced relation by the members 35 and bolts 36. A doorway is formed in the walls 27 and 28 and is normally closed by the double-walled door 37 which is hinged to the wall 28, as indicated at 38, and is secured in closed position by means of the button or latch 39. At 40 I have indicated a ring or handle on the door 37, by means of which it may be conveniently opened and closed.

A fuel reservoir 41 which may be of the usual construction consisting of an inverted glass bottle having a check valve 42, is supported on the sump 24, as indicated in Figs. 3 and 4, and this reservoir may be provided with a hoop 43 having an outwardly project-

ing lug 44 thereon adapted to engage with a hook 45 on the door 37 for the purpose of supporting the reservoir 41 in an upright position.

5 When it is desired to remove or replace the reservoir 41, the door 37 is swung open to a substantially horizontal position and supported in this position by the lower edge of the opening for the casing doors 15. The 10 reservoir 41 is thereby swung to a horizontal position and the lug 44 may be detached from the hook 45. In order to insure the maintenance of the reservoir 41 in the upright position and to properly support it 15 on the door 37, when the latter is open, a rest 46 may be provided on the door near the lower end of the reservoir. When the reservoir is removed from the sump 24, by opening the door 37, the valve 42 is automatically 20 closed and when the reservoir is replaced on the sump, by closing this door, the valve 42 is automatically opened on account of engaging with the bottom of the sump, according to the usual practice.

25 The upper part of the wall 28 is provided with a series of openings 47 to permit air to circulate upwardly through the jacket space 29 and be discharged through the perforations in the cap 33. The space 29 is 30 open at the lower ends of the walls 27 and 28 to permit the relatively cool air from below the stove to enter the space 29 and the circulation of this cool air through the jacket of the chamber 30 effectively insulates the 35 latter from the heat of the burners. A series of openings 48 may be provided in the top 16, around the cap 33 for the purpose of ventilating the space above the cover 31.

By the improved construction which I 40 have devised the fuel reservoir and the burners being supported on the block 21 are freely rotatable as a unit so that any of the burners may be brought to the front of the stove for the purpose of lighting or cleaning them. After any particular burner has 45 been lighted it may be swung to a position below one of the openings 17, at the rear of the stove, so that in this manner, I have provided a compact arrangement which has 50 all of the convenience, so far as accessibility is concerned, of the ordinary arrangement in which all of the burners are arranged in a line close to the front of the stove. By having the fuel reservoir at the center of the 55 stove the supply pipes for conveying the fuel to the different burners may be all of the same length and therefore provide for a uniform supply of fuel to all of the burners. It will also be noted that in rotating the 60 group of burners the fuel supply connections are in nowise disturbed.

The construction which I have devised has the additional advantage of permitting any of the burners to be used with any of the 65 openings in the top of the stove so that, in

case any particular burner is out of order, the other burners may be arranged, as desired, under any three of the openings 17.

Having described my invention, what I claim is:

1. In stoves of the character described, the combination of a casing, a top on said casing having burner openings therein, a step-bearing in said casing, a member rotatable on said step-bearing, a fuel chamber above said member and the wall of which rotatably engages an opening in said top, and a plurality of burners carried by said member and rotatable therewith. 70

2. In stoves of the character described, the combination of a casing, a top on said casing having burner openings therein, a step-bearing in said casing, a member rotatable on said step-bearing, a fuel chamber above and connected with said member and having jacketed walls through which air is adapted to circulate upwardly, and a plurality of burners carried by said member and rotatable therewith. 80

3. In stoves of the character described, the combination of a casing, a top on said casing having burner openings therein, a step-bearing in said casing, a member rotatable on said step-bearing, a fuel chamber above and connected with said member and having jacketed walls through which air is adapted to circulate upwardly and into the upper part of said chamber, means for venting said chamber through said top, and a plurality of burners carried by said member and rotatable therewith. 90

4. In stoves of the character described, the combination of a casing, a top on said casing having burner openings therein, a step-bearing in said casing, a member rotatable on said step-bearing, a fuel chamber above and connected with said member and having jacketed walls through which air is adapted to circulate upwardly and into the upper part of said chamber, said chamber having a cover that is provided with an upwardly projecting flange rotatably arranged in an opening in said top, a fuel basin carried by said member, fuel pipes radiating from said member, and burners on said pipes. 100

5. In stoves of the character described, the combination of a casing, a bearing support therein, a bearing member rotatable on said support about a vertical axis, a fuel reservoir on said member, a container for said reservoir mounted on said member and having its upper end rotatably supported, fuel pipes radiating from said member, and burners on said pipes. 110

6. In stoves of the character described, the combination of a casing, a bearing support therein, a bearing member rotatable on said support about a vertical axis, a fuel reservoir on said member, a hollow-walled 120

5 container for said reservoir mounted on said member and having its upper end rotatably supported, vent openings permitting the circulation of air upwardly through said container and its walls, fuel pipes radiating from said member, and burners on said pipes.

7. In stoves of the character described, a fuel chamber having a sump therein, a 10 plurality of burners arranged about said

chamber and having fuel pipes supplied from said sump, a door in the wall of said chamber hinged thereto along the lower edge of the door, and a fuel reservoir suspended on said door and movable therewith to and 15 from its normal position over said sump.

In testimony whereof, I hereunto affix my signature.

PAUL W. COPPOCK.
